HYDRAULIC RIVETING MACHINE

Loyd A. Ward, Jackson, Mich., assignor to
 Tomkins-Johnson Company, Jackson, Mich., a
 corporation of Michigan

Application June 3, 1938, Serial No. 211,500

9 Claims. (Cl. 78—48)

This invention relates to riveting machines and more particularly to riveting machines hydraulically actuated and designed for work on aluminum alloy constructions, such as in aircraft manufacture.

In the production riveting of aircraft structures and the like great uniformity and precision are essential. It has been found that these desiderata, together with speed of operation, can be obtained by the use of a riveting machine wherein the rivet is suspended beneath a downwardly facing anvil, to receive the work thereon prior to heading up, and providing an upwardly facing set which is hydraulically actuated to upset the rivet on the work. The present invention includes these features, and the structures disclosed are illustrative of ways in which the invention can be carried out.

An object of the invention is to provide a riveting machine having structure to support a rivet beneath a downwardly facing anvil, and an upwardly movable set to head up the rivet.

Another object of the invention is to arrange the rivet supporting structure for movement away from its supporting position between the anvil and the set after the rivet has been received in the work.

A further object of the invention is to provide means for disposing a rivet in operative relation to a flat riveting surface and to remove the disposing means when the rivet is suitably supported in the work.

A still further object of the invention is to provide rivet supporting means movable from one station to another to receive a rivet.

A still further object of the invention is to provide a work support to hold work against the riveting anvil.

These and other objects will be apparent from the following specification when taken with the accompanying drawings, in which:

Fig. 1 is a broken vertical section of one form of the invention,

Fig. 2 is a section on the line II—II of Fig. 1,

Fig. 3 is a view taken on the line III—III of Fig. 2,

Fig. 4 is a detailed view of the rivet support, from which selected rivets are picked up by the rivet carrier,

Fig. 5 is a partial vertical section of another form of the invention,

Fig. 6 is a side view of the structure shown in Fig. 5,

Fig. 7 is an elevation and partial vertical sec-

tion of the anvil and anvil actuating mechanism of the structure disclosed in Figs. 5 and 6,

Fig. 8 is a partial vertical section of still another form of the invention,

Fig. 9 is a partial side view of the structure shown in Fig. 8 partly broken away to show details, and

Fig. 10 is a partial vertical section of the structure disclosed in Fig. 8 showing, in addition, the control apparatus.

Referring particularly to Figs. 1, 2, 3 and 4 of the drawings, there is disclosed one form of the invention wherein the rivet is moved under a flat anvil 1 by a resilient cantilever leaf spring rivet carrier 2. The anvil 1 is downwardly facing and has a relatively expansive surface 3, which is flat and arranged to be disposed next to the outside of the work so that when the riveting is completed, a smooth, stream-lined surface will be provided, unbroken by usual projecting rivet heads. The anvil 1 is fixedly mounted in a frame 5.

The cantilever leaf spring rivet carrier 2 is actuated laterally by a piston 6 in a cylinder 7 through a piston rod 8 connected with the piston 6 and projecting from one end of the cylinder 7 through a packing 9. The portion of the piston rod 8 outside of the cylinder 7 is connected to a member 10 by a screw 11. The member 10 is in turn connected to a plate 12 by a screw 13. The plate 12 is slidably disposed on the top of a plate 14, which is a part of the frame 5. Depending from the plate 12 through a slot 15 in the plate 14 is a carriage 16, to which is secured by screws 17 the rivet carrier 2. The slot 15 serves as a guide for the carriage 16, so that when the piston 6 is reciprocated in the cylinder 7 the carriage 16 is reciprocated in the slot 15.

It will be observed that the frame 5 has a curved portion 20 and that the cantilever leaf spring rivet carrier 2 has an initial set. Said set, when the carriage 16 is in retracted position, as disclosed in dotted outline in Fig. 1, is such that the cantilever leaf spring rivet carrier 2 is disposed resiliently pressed against the lower side of the rivet supporting member 21, with the forked end with which it is provided straddling a rivet therein. As the carriage is advanced toward its full line position, as shown in Fig. 1, the rivet carrier 2 pushes a rivet from the rivet supporting member 21, out through the slot 22 therein, and along the curved surface 20 until it is disposed beneath and against the anvil 3, as shown in Fig. 1.

The selecting mechanism for disposing rivets

one at a time in the rivet supporting member 21 is essentially that disclosed in the copending application of Loyd A. Ward et al., Serial No. 192,946, filed February 28, 1938. The selecting mechanism is disclosed particularly in Figs. 2, 3 and 4 and comprises a selector or shuttle 23 having communicating therewith a chute 24, into which rivets are fed either manually or from a hopper. The actuation of the shuttle or selector 23 is such that each time it is moved to the right, as shown in Fig. 3, a single rivet from the chute 24 is selected and dropped down the chute 25 to the rivet supporting member 21 and at one end of the outlet slot 22. Reciprocating movement is given to the selector 23 as follows: A rod 26 is slidably mounted in a frame portion 27. Disposed on the rod 26 are adjustable stops 28 and 29, between which is arranged to slide a projection 30 from the member 10 connected to the piston rod 8, as disclosed in Figs. 1 and 3. Also disposed on the rod 26 are stops 31 and 32 adjacent each end of the selector 23, so that as the rod 26 is reciprocated, the selector 23 also reciprocates. The position of the stops 28 and 29 is such that as the piston rod 8 reciprocates to reciprocate the carriage 16 and the rivet carrier 2, it also reciprocates, through the projection 28, the rod 26, and thus the selector 23, by alternately abutting against the stops 28 and 29. Thus, as the rivet carrier 2 is withdrawn to its retracted position, as shown in dotted outline in Fig. 1, a rivet is selected from the chute 24 by the selector 23 and passes down the chute 25 to position in the rivet supporting member 21 to be picked up by the forked end of the rivet carrier 2 the next time it moves forward or to the left, as shown in Fig. 1.

A set 35 for upsetting the rivet held by the rivet carrier 2 against the anvil 3 is mounted on the upper end of a hydraulic piston rod 36 actuated by a hydraulic piston 37 disposed in a cylinder 38. The piston rod 36 is guided for reciprocation in a tube 39. Cooperating with the set 35 is a conventional stripper 40 resiliently urged by a spring 41.

In the operation of the riveting machine, work 42, shown in broken line in Fig. 1, is disposed on a work rest, comprising posts 43 projecting from a platform 44 mounted on a sleeve 45 slidable on the outside of the tube 39. While only two posts 43 have been illustrated, it is contemplated that as many or few posts may be used as desired. Slidable on the outside of the sleeve 45 is a collar 46, having pivoted thereto a clevis 47. The clevis 47 is connected by a rod 48 to another clevis 49, which is in turn pivoted to a foot pedal 50 pivoted to a bracket 51 mounted on the base 52. Disposed about the sleeve 45 and between the platform 44 and the collar 46 is a helical spring 53. Vertical movement is given to the collar 46 and through the spring 53 to the platform 44 and the work supporting posts 43 by actuation of the foot pedal 50.

Work 42 disposed on the work supporting posts 43 is provided with a rivet receiving hole 55, which is countersunk to receive the head of the rivet. The foot pedal 50 is moved sufficiently to lightly urge the work 42 against the rivet held in the rivet carrier 2 and backed up by the anvil 3. The work 42 is then moved until the rivet is disposed in the hole 55. At this point of the operation, continued movement of the foot pedal 50 urges the work 42 up against the anvil 3. As the work moves toward the anvil 3, it strikes a finger 59, which actuates mechanism to with-

draw the rivet carrier 2 to the position shown in dotted outline in Fig. 1.

The mechanism for withdrawing the rivet carrier 2 comprises, in conjunction with the finger 59, a pressure releasing valve 60 having an actuating button 61 and a conduit 62, providing a communication with the distributing valve 63. The distributing valve 63 is similar to the distributing valve disclosed in the copending application of Harold A. Tomkins et al., Serial No. 36,106, filed June 19, 1936, now Patent No. 2,132,811.

The distributing valve 63 comprises a body, within which is reciprocable a piston 64 having ends 65 and 66. Between the ends 65 and 66 is a space 67, which comprises a distributing port. The end 66 is provided with a reduced extension 68 of less cross-sectional area than the cross-sectional area of the end 65. An inlet supply port 69 and outlet ports 70 and 71 both project through the body of the distributing valve 63. At the end of the body adjacent the end 65 is a chamber 72, which is larger in cross-sectional area than the cross-sectional area of a chamber 73 provided adjacent the reduced extension 68. A leakage port 74 provides a communication between the space 67 and the chamber 72, and a leakage port 75 provides a communication between the space 67 and the chamber 73. It will be observed that the conduit 62 from the pressure releasing valve 60 communicates with the chamber 72.

As shown in Fig. 1, the inlet port 69 is connected by the space 67 with the outlet port 71, which is in turn communicating with a conduit 80 communicating with the right end of the cylinder 7. Thus, compressed air from the inlet port 69 is directed into the cylinder 7 and is holding the piston 6 against the left end of the cylinder 7. When the work 42 strikes against the finger 59, the finger 59, being slidably mounted on the body 5, presses on the button 61 to exhaust compressed air through the conduit 62 from the chamber 72. The result is that the full pressure in the chamber 73 moves the piston 64 to the left end of the body of the distributing valve 63. Compressed air from the inlet port 69 is then directed by the space 67 into the outlet port 70, which communicates with a conduit 81 connected to the left end of the cylinder 7. The result is that the piston 6 is moved to the right, as viewed in Fig. 1, through the piston rod 8, the member 10, the plate 12, and the carriage 16. The rivet carrier 2 is moved to the dotted line position, as shown in Fig. 1.

It will be observed that the rivet carrier 2 is withdrawn as the work 42 is moved toward the anvil 3. When the rivet carrier 2 has been withdrawn, the work 42 is clamped against the anvil 3 through the action of the pedal 50 and the spring 53. The work 42 and rivet are now ready for heading up. A foot pedal 82 connected by a rod 83 to a conventional hydraulic distributing valve 84 is actuated. The connections between the distributing valve 84 and the cylinder 38 are such that when the pedal 82 is actuated, hydraulic fluid under pressure is conducted from a source of the port 85 on the cylinder 38. The piston 37 is then moved upwardly to urge the set against the rivet to upset the same, and hydraulic fluid is exhausted from above the piston 37 through the port 86. The conventional hydraulic distributing valve 84 is of the character wherein when a predetermined pressure has been reached, the hydraulic fluid under pressure from

the source is conducted to the port 86, and the port 85 is connected with an exhaust, to lower the piston 31, and thus the set 35, to its original starting position.

When the set 35 is lowered, the work 42 is lowered by the operator removing pressure from the pedal 50, thereby permitting the finger 59 and the push button 61 to move downwardly to close the exhaust valve 60. Then, since the area on the piston end 68 is less than the area of the piston end 65, the piston 64 is moved to the position shown in Fig. 1, thereby cutting off the supply of compressed air from the inlet port 69 to the port 70 and conduit 81 and directing compressed air from the inlet port 69 to the port 71 and conduit 80 to return the piston 6 to the position shown in Fig. 1 at the left end of the cylinder 1, and thus to cause the rivet carrier 2 to pick up a rivet from the rivet support 21 and to present it, as shown, beneath the anvil 3. It will be understood that when the piston 64 is moved to cover the port 70, exhaust air will be exhausted from the cylinder 1, through the conduit 81, through the exhaust passage 87 in the surface of the piston end 65, and out of the exhaust port 88 in the body of the distributing valve 63. In a like manner air is exhausted from the cylinder 1 when the piston 64 moves to the opposite end of its stroke, through the exhaust channel 89 corresponding to the exhaust channel 87 and the exhaust port 90 corresponding to the exhaust port 88, all in the manner disclosed in the aforesaid copending application of Harold A. Tomkins et. al., Serial No. 86,106, filed June 19, 1936, now Patent No. 2,132,811.

The form of the invention just described is particularly desirable wherein it is a requirement that the exterior surface of the riveted structure be smooth and free from projecting rivet heads. It will be clear that the broad anvil surface 3 and the countersunk work 42 for receiving a rivet head adjacent the anvil 3 will leave a finished riveted surface smooth and stream-lined in every respect.

Another form of the invention is disclosed in Figs. 5, 6, and 7. In this form of the invention the work to be riveted is manipulated to dispose a rivet held in clamping jaws 95 in a rivet hole in the work. The jaws 95 are of the character disclosed in my copending application, Serial No. 101,210, filed September 17, 1936, and are mounted on depending cantilever leaf springs 96 secured on opposite sides of a block 97 slidable in a vertical passageway 98. The jaws 95, the cantilever leaf springs 96 and the block 97 are arranged to move upwardly and to be spread by the anvil 99 when the set 100 is moved upwardly to upset the rivet. The jaws 95 are thus moved completely out of position between the anvil 99 and the set 100.

Movement of the set 100 is accomplished by a hydraulic piston 101 acting against a piston rod 102 connected to the set 100. The piston 101 reciprocates in a cylinder 103 under the control of a hydraulic distributing valve 104, which is actuated by a foot pedal 105. The valve 104 is similar to the valve 84 disclosed in Fig. 1 and is arranged to conduct hydraulic fluid under pressure from a source 106 through a conduit 107 into the cylinder 103 beneath the piston 101 to move the piston rod 102 and thus the set 100 upwardly. At the same time, exhaust hydraulic fluid from the cylinder 103 above the piston 101 is exhausted through the conduit 108, the valve 104 and the outlet 109. When a predetermined pressure has

been reached, the valve 104 automatically acts to admit hydraulic fluid from the source 106 to the conduit 108 into the cylinder 103 above the piston 101 to withdraw the set 100. At the same time fluid is exhausted from the lower side of the cylinder 103 to the conduit 107 and the outlet 109 of the valve 104.

The valve 104 is also provided with a compressed air distributing valve 110, conventional in structure and arranged to conduct air from a compressed air source 112 through the conduit 113 to the upper end of a cylinder 114, in which is disposed a piston 115 having connected thereto a piston rod 116. The piston rod 116 has connected to the lower end thereof a yoke 117, to the ends of which are connected rods 118 and 119.

The function of the piston 115, and the rods 118 and 119 which it controls, is for moving the rivet clamping jaws 95 downwardly into rivet clamping position and to prepare the jaws 95 for receiving another rivet for the next riveting operation. The rod 118 is movable vertically in the vertical passageway 98 and is arranged to engage with the top of the block 97 to force the same downwardly, thereby forcing the jaws 95 downwardly off the anvil 99, on the opposite sides of which they have been forced by the upcoming work pushed by the set 100. It will be clear that when the jaws 95 are disposed on opposite sides of the anvil 99, they are spread apart and resiliently urged against the sides of the anvil 99 by the leaf springs 96. In order to keep the jaws 95 spread apart after they have moved to their lower position so that a new rivet may be disposed therebetween, a wedge 120 at the lower end of the rod 119 is arranged to move between the jaws 95 while they are still spread apart by the anvil 99. It will thus be clear that the normal distance between the top of the jaws 95 and the bottom of the wedge 120 is less than the distance between the bottom of the rod 118 and the top of the block 97. Thus, by the time the rod 118 strikes the top of the block 97, the wedge 120 will already have moved into position between the jaws 95 to hold them apart.

The valve 110 is arranged to operate in such a manner that as the valve 104 reverses the movement of the piston 101 to move it downwardly, compressed air is admitted through the valve 110 and the conduit 113 to the cylinder 114 to lower the piston 115 with the results described. By the time the piston 101 reaches the bottom of its stroke, the distributing valve 104 automatically operates to disconnect the inlet 112 from the conduit 113 and to connect the conduit 113 to the exhaust 121 to exhaust compressed air from the cylinder 114. The result is that the spring 122, bearing against the piston 115 and the lower end of the cylinder 114, resiliently urges the piston 114, and together with it the piston rod 116, the yoke 117 and the rods 118 and 119, into their upper positions. However, in the meantime, selecting mechanism 125 has been actuated to dispose a new rivet between the jaws 95, so that as the rod 119 is raised from between the jaws 95, the new rivet is clamped therebetween and is ready to receive the work thereover.

The rivet selecting mechanism 125 comprises a transversely movable shuttle or selector 126 of the character described in the copending application of Loyd A. Ward et al., Serial No. 192,946, filed February 28, 1938. The selector 126 is associated with a chute 127 and is moved laterally to select a rivet from the chute 127 and to let it fall

by gravity down the chute 128 to position it between the jaws 95.

The mechanism for laterally reciprocating the selector 126 comprises a lever 130 oscillatable about a pivot 131 and yieldingly urged upwardly by a spring 132. The lever 130 has connected thereto a leaf spring 133, which is in operative engagement with a horizontally slidably member 134 reciprocable horizontally as the lever 130 is oscillated about the pin 131. The opposite end of the member 134 is provided with an outwardly extending cantilever leaf spring 135 disposed in a slot 136 in the selector 126. The lever 130 is oscillated about the pin 131 by a shoulder 137 comprising a portion of the rod 119. Thus, as the rod 119 moves downwardly under the action of the piston 115 and the piston rod 116, the lever 130 is oscillated downwardly against the action of the spring 132 to move the leaf spring 133 to laterally move the member 134, which, through the leaf spring 135, laterally moves the selector 126 to select a single rivet from the chute 127 to let it fall by gravity into the chute 128. It will be understood that as the piston 115 moves upwardly to move the rod 119 upwardly to remove the wedge 120 from between the jaws 95 to clamp the rivet therebetween, the lever 130 is moved upwardly under the action of the spring 132 to set the selector 126 for the next selecting operation.

The operation of the invention is as follows: The work is moved over the rivet held between the jaws 95. The operator then moves down the foot pedal 105, which admits hydraulic fluid to the cylinder 103 to move the piston 101 upwardly to upset the rivet by means of the set 100. The set 100 has operatively associated with it a conventional stripper 138. As the set 100 moves the work upwardly, the jaws 95 are spread over the anvil 99 until they are out of position between the anvil 99 and the set 100. When a predetermined pressure has been reached, the hydraulically controlled valve 104 automatically acts to return the piston 101 to its lower or starting position. At the same time the compressed air distributing valve 110 admits compressed air through the conduit 113 to the top of the cylinder 114 to move the piston 115, and together with it the rods 118 and 119, downwardly. The downward movement of the rod 119 disposes the wedge 120 between the jaws 95 to maintain them spread apart while the rod 118 abuts against the top of the block 97 to move the jaws 95 down into starting position. As the rod 119 moves downwardly, the shoulder 137 thereon actuates the selecting mechanism 125 through the lever 130 to move the selector 126 to dispose a rivet from the chute 127 into position between the jaws 95. At the time the piston 101 reaches its lowermost position, the compressed air distributing valve 110 acts to automatically exhaust the compressed air from the top of the cylinder 114 to permit the spring 122 to move the piston 115, and thus the piston rod 116, and the rods 118 and 119, upwardly to permit the leaf spring 96 to clamp the jaws 95 against the rivet held therebetween for the next riveting operation. It will be understood that if desired, the work supporting posts 43 disclosed in Fig. 1 and their associated structure may be employed in association with the set 100 and the stripper 138.

Still another form of the invention is disclosed in Figs. 8, 9 and 10. In this form of the invention the rivet is clamped between jaws 145

mounted on cantilever leaf springs 146 connected to a sliding block 147. Mounted for movement relatively to the jaws 145 is a ram 148 in which is mounted an anvil 149. The anvil 149 and the ram 148 are arranged for relative movement by structure illustrated in my copending application, Serial No. 101,210, filed September 17, 1936. The relative movement of the jaws 145 and the anvil 149 is such that when the jaws are in their lowered position, as determined by the stop 150 under the control of the adjusting screw 151, as disclosed in my aforesaid copending application, the anvil 149 is in the position disclosed in Fig. 9, that is, adjacent the bottom of the jaws 145, backing up the rivet while it is clamped laterally by the jaws 145. When the jaws 145 are in their upper position, as shown in dotted outline in Fig. 9, the anvil 149 is in the position shown, that is, above the jaws 145 to permit a rivet selected by the selector 152 from the chute 153 to slide down the chute 154 to drop into the top of the jaws 145. Then, as the anvil 149 moves downwardly under the action of the ram 148, the rivet between the jaws 145 is forced downwardly until it reaches the position shown in full line in Fig. 9. Since the lower position of the anvil 149 is always the same, the relative lower positions of the anvil 149 and the jaws 145 are determined by the vertical adjustment of the jaws 145 by the varying of the position of the stop 150 against which the block 147, carrying the cantilever leaf spring 146, abuts.

The rivet as shown in Fig. 9 is ready to have moved upwardly thereover the work 155. When the work has been placed over the rivet, the anvil 156 moves upwardly under the action of a piston, such as the piston 37 disclosed in Fig. 1, or 101 disclosed in Fig. 7. The anvil 156 has associated therewith a suitable stripper 157. As the anvil 156 and the stripper 157 move upwardly, the work bearing against the jaws 145 spreads them over the anvil 149 to move them out of the way. The rivet is then headed up in the usual manner.

It is preferred that the movement of the anvil 156 be under the control of an automatic hydraulic distributing valve, such as the valve 84 in Fig. 1, which returns the anvil 156 to its starting position when a predetermined pressure has been reached. Also, the anvil 156 may be associated, if desired, with a work support such as is disclosed in Fig. 1.

The rivet selector 152 is actuated upon the movement of the ram 148. The structure for actuating the selector 152 may be that disclosed in Figs. 5 and 6 or may be under the control of the piston rod 160, employed in a manner to be described, for reciprocating the ram 148. The operative connection between the piston rod 160 and the selector 152 may be that disclosed particularly in Fig. 3 hereof in the form of the projection 30 of the member 10.

The mechanism for reciprocating the ram 148 is disclosed particularly in Figs. 8 and 10 and comprises a toggle consisting of a link 161 and a bell crank lever 162 connected by a pivot 163 to the piston rod 160. The piston rod 160 is actuated by a piston 164 in a cylinder 165. The cylinder 165 is pivoted at one end by a pivot 166 to the frame 167 and oscillates about the pivot 166 as the piston 164 moves from one end of the cylinder 165 to the other. Movement of the piston 164, and thus the toggle comprising the members 161 and 162 and the ram 148, to which the toggle is pivoted by a pin 168, is under the

control of an air distributing valve 170, which is substantially identical with the distributing valve 63 disclosed in Fig. 1. Operation of the distributing valve 170 is under the control of a push button exhaust valve 171. A conduit 172 connects the exhausting valve 171 with the chamber 173 of the distributing valve 170. When the push button valve 171 is opened, the distributing piston 174 of the distributing valve 170 moves to the left, as viewed in Fig. 10, to conduct compressed air from a source 175 through the distributing chamber 176, through the conduit 177 to the left end of the cylinder 165 to drive the piston 164 to the right and thus through the toggle raise the ram 148. As the ram 148 is raised, the jaws 145 move upwardly under the action of the rod 178, which is connected to the ram 148 in a manner disclosed in my aforesaid copending application Serial No. 101,210, filed September 17, 1936. At the same time the selector 152 is actuated to deposit a rivet from the chute 153 in the top of the jaws 145, as disclosed in dotted outline in Fig. 9. Release of pressure on the push button valve 171 results in the distributing piston 174 moving to the right due to the differential pressure areas at the ends of the piston 174 in the chamber 173 and the chamber 179. Compressed air is then conducted from the source 175, through the distributing chamber 176, through the conduit 180 to the right end of the cylinder 165, to drive the piston 164 to the left and to move the ram 148 downwardly. The exhaust ports 181 and 182 of the distributing valve 170 are provided with petcocks 183 and 184, which may restrict or open the exhaust passage to control the speed of movement of the piston 164 in a known and conventional manner. The reason for controlling this speed is to control the speed of movement of the anvil, so as to allow sufficient time for a rivet from the chute 153 to be deposited in the jaws 145 through the action of the selector 152, while the ram 148 is moving up and down automatically.

In operation, starting with the apparatus in the position disclosed in Fig. 9, the work is disposed over the rivet. The set 156 is then moved upwardly to upset the rivet, the set 156 automatically returning to its starting position under the control of an automatic valve, as set forth. The push button exhaust valve 171 is then actuated to raise the ram 148 and the set 149, together with the jaws 145, as described, and a rivet from the chute 153 is deposited in the jaws 145. The set 149 and ram 148 are automatically returned to the position shown in Fig. 9 to present the rivet received from the chute 153 to receive the work for the next operative step of the machine.

From the foregoing description it will be clear that the present invention is not limited to a single form of structure but that it may take numerous forms, a number of which have been described in detail. It will be further understood that where automatic and semi-automatic controls have been used, other controls of a like nature performing equivalent functions may be used if desired. While it has been hereinabove set forth that the present invention is particularly adaptable for use on aluminum alloy constructions and in aircraft manufacture, it is to be understood that the invention is not limited to any of these uses.

Having thus described my invention, what I desire to secure by Letters Patent and claim is:

1. In a riveting machine, a downwardly facing

anvil, means for supporting a rivet, a selector for depositing at predetermined times a rivet on said support, a rivet carrier movable in a fixed path, means for actuating said selector to deposit a rivet on said support and in a position having a portion extending into the path of movement of said carrier, and means to move said carrier past said support and into co-operative engagement with the projecting portion of a rivet on said support to pick up and remove said rivet from said support as it moves thereby and to carry said rivet into operative relation to said anvil, an upwardly facing set, and means to move said set upwardly to upset the rivet against said anvil.

2. In a riveting machine, a downwardly facing anvil, means for supporting a rivet, a selector for depositing at predetermined times a rivet on said support, a rivet carrier, a cylinder, a piston disposed in said cylinder and reciprocable therein under the control of a movable part of the machine for automatic operation, means connected to said piston for actuating said selector and said carrier, said carrier being actuated on one stroke of the piston to pick up a rivet from said support and to dispose the same in operative relation to said anvil, and during the other stroke thereof to withdraw said carrier to its starting position, an upwardly facing set, and means to move said set upwardly to upset the rivet against said anvil.

3. In a riveting machine, a downwardly facing anvil, means for supporting a rivet, a carriage, a cantilever leaf spring secured to said carriage, said leaf spring having rivet supporting means on the free end thereof, means to actuate said carriage to move said cantilever leaf spring into engagement with the rivet on said supporting means to pick up said rivet and to dispose the same in operative relation to said anvil, an upwardly facing set, and means to move said set upwardly to upset the rivet against said anvil.

4. In a riveting machine, a downwardly facing anvil, means for supporting a rivet, a carriage, a cantilever leaf spring secured to said carriage, said cantilever leaf spring having rivet supporting means on the free end thereof and also being provided with a predetermined set, said carriage being reciprocable in a horizontal plane above the horizontal plane of the operative surface of said anvil, said machine having a surface coincident with the horizontal plane of the operative surface of said anvil, and continuing in a curved path into substantial coincidence with the plane of the path of movement of said carriage, said predetermined set of said cantilever leaf spring urging the same against said surface, means to actuate said carriage to move said cantilever leaf spring to pick up a rivet from said rivet support and move the same along said surface until it is disposed beneath and against said anvil, an upwardly facing set, and means to move said set upwardly to upset the rivet against said anvil.

5. In a riveting machine, an anvil, means for supporting a rivet, a selector for depositing at predetermined times a rivet on said support, a carriage, a cantilever leaf spring secured to said carriage, said cantilever leaf spring having rivet supporting means on the free end thereof and also being provided with a predetermined set, said carriage being reciprocable in a horizontal plane back of the horizontal plane of the operative surface of said anvil, said machine having a surface coincident with the horizontal plane

of the operative surface of said anvil and continuing in a curved path into a substantial coincidence with the plane of the path of movement of said carriage, said predetermined set of said cantilever leaf spring urging the same toward said surface, means to actuate said selector to deposit a rivet on said rivet supporting means and to move said carriage to move said cantilever leaf spring to pick up a rivet from said rivet support and move the same along said surface until it is disposed in operative relation to said anvil, a set, and means to move said set to upset the rivet against said anvil.

6. In a riveting machine, a downwardly facing anvil, means for supporting a rivet, a laterally movable rivet carrier movable in a fixed path, a rivet held by said support having a portion projecting into the path of said carrier, means to move said carrier past said supporting means into co-operative engagement with the projecting portion of a supported rivet to pick up said rivet from said supporting means as it moves by the same and to carry said rivet into operative relation to said anvil, an upwardly facing set, a work support associated with said set, means to move said work support upwardly independently of said set to dispose work on said rivet, and means to move said set upwardly to upset the rivet against said anvil.

7. In a riveting machine, an anvil, means for supporting a rivet, a reciprocable carriage, a cantilever leaf spring secured to said carriage, said cantilever leaf spring having rivet supporting means on the free end thereof and also being provided with a predetermined set, said carriage being reciprocable in a plane inwardly of and parallel to the plane of the operative surface of said anvil, said machine having a surface coincident with the plane of the operative surface of said anvil and continuing in a curved path to 40 substantial coincidence with the plane parallel

to and adjacent the plane of reciprocation of said carriage, said rivet supporting means being adjacent said last named plane, said predetermined set of said cantilever leaf spring urging the same toward said surface, and means to move said cantilever leaf spring to pick up a rivet from said rivet support and move the same along said surface until it is disposed in operative relation to said anvil, a set, and means to move said set to upset the rivet against said anvil.

8. In a riveting machine, a downwardly facing anvil, means movable from a position at one side of said anvil into a position for supporting a rivet in operative relation to said anvil for receiving work thereon, mechanism for moving said supporting means, controlling means for said mechanism, an upwardly facing set, said supporting means in rivet supporting position being between said anvil and said set, means controlled by the movement of the work when being moved into operative relation with the rivet supported by said supporting means for actuating said controlling means for laterally withdrawing said supporting means from between said anvil and said set when the rivet is received in the work, and means for moving said set upwardly to upset the rivet against said anvil.

9. In a riveting machine, a downwardly facing anvil, means for supporting a rivet, a rivet carrier, means to actuate said carrier to pick up a rivet from said support and to dispose the same in operative relation to said anvil, an upwardly facing set, means controlled by the movement of the work when being moved into operative relation with the rivet supported by said carrier, for withdrawing said carrier when the rivet is received in the work, and means to move said set upwardly to upset the rivet against said anvil.

LOYD A. WARD.
